UNITED STATES PATENT OFFICE

EDWIN G. FRANCK, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE

CAR ROOF

Application filed June 15, 1925. Serial No. 37,260.

This invention relates to car roofs and more particularly to an improved form of carline and associated structure.

The invention has among its objects to simplify, render more efficient, and improve generally constructions of this type, and these as well as other objects, advantages, and novel features of construction will be made more apparent as this description proceeds, especially when considered in connection with the accompanying drawings, wherein

Figure 1 is a fragmentary top plan view of a car roof constructed in accordance with my invention and showing progressive steps of assembly,

Figure 2 is an enlarged fragmentary transverse sectional view taken substantially on the plane indicated by the line 2-2 in Figure 1,

Figure 3 is a fragmentary side elevation with certain parts removed, and

Figure 4 is an enlarged detailed sectional view taken substantially on the plane indicated by the line 4-4 in Figure 1.

Referring now particularly to the drawings wherein like reference characters indicate like parts it will be noted that the frame includes side plates 10, purlines 11 and a ridge pole 12. The sides of the car are formed by sheathing 13 suitably connected at the top to the side plates 10.

The transverse frame members or carlines 14 are in the form of inverted T-bars having a head or base portion 15 and an upstanding or stem portion 16. The carlines 14 extend from side plate to side plate and engage the purlines and ridge pole in the customary manner. The carlines and purlines are se-

cured together by means of bolts 17 which pass through the inverted head or base portion 15 and through the purlines, while the carlines are secured to the ridge pole by means of bolts 18 passing through the base of the carline and through the ridge pole in

a similar manner. Each purline 11 is preferably transversely notched or recessed as at 19 for the accommodation or reception of the base 15 of the carline.

The outer ends of the carlines 14 are secured to the side plates by flanges 20 formed by bending the base 15 angularly and in a downward direction with reference to the general plane thereof, as particularly shown in Figure 2. The web portion 16 of each carline at the end thereof is preferably cut off at an angle as shown at 21, thus providing a portion which may be conveniently bent to form the flange 20. These flanges lie against the outer face of the side plates 10 and cooperating therewith are carline brackets 22 in the form of angle plates which are secured as for instance by rivets 23 to the base of the carline. The downward extending portion of each carline bracket is apertured as is the flange 20, these apertures registering for the reception of a bolt 25 which passes therethrough and through the side plate 10. With this construction the carline is permitted to rest upon the top face of the side plates 10 while the side plate is securely clamped between the flange 20 of the carline and the carline bracket 22.

The roof sheets 26 are arranged between the spaced carlines 14 in the customary manner and are provided with upstanding edge portions 27 joined by intermediate inclined portions 28 to the main portions of the roof sheets. The intermediate or inclined portions 28 lie over the base or inverted head portion of the adjacent carline while the upstanding edge portions 27 are arranged substantially parallel to the stem portion 16 of the carline.

The car roof herein shown is of the flexible type so that the roof sheets 26 are not rigidly fixed but are permitted to enjoy a limited lateral movement. For holding these roof sheets in place and for weatherproofing the joints therebetween there is associated with

each carline 14 a carline cap or transverse cap 29 having a restricted channel portion 30 which embraces the upper end of the stem 16 of the carline and which is shaped further to provide an intermediate portion 31 formed by vertical walls spaced from the stem 16 of the carline, this transverse cap terminating in outwardly turned edge portions or flanges 32 which engage the roof sheets at the inclined portions 28 thereof. While the transverse caps 29 waterproof the joints between adjacent roof sheets and hold these roof sheets in place upon the roof frame sufficient space is provided between the vertical wall of portion 31 and stem 16 of the carline to permit of lateral movement of the roof sheets and consequently of the upstanding edge portions 27. The transverse caps are rigidly secured to the carlines by means of rivets or other suitable means 33, see particularly Figure 4.

The side edges of the roof sheets are provided with return-bent edges 34 which engage under the return-bent portions of eave flashing strips 35 while the transverse caps are tapered off at their ends to form flat portions 36 bent inwardly as at 37 to engage under the return-bent edges of the roof sheets, see particularly Figure 2.

30 The running board 38 is supported by running board saddles 39 in the form of angle plates which are riveted or otherwise suitably secured to the upstanding portion 16 of the carlines and are secured as by bolts 40 to the running boards. In practice the same securing means 33 employed for securing the transverse caps to the carlines may be employed for connecting the running board saddles to the carlines.

40 In Figure 1 the progressive steps of assembly have been illustrated, it being noted that at the extreme left of this figure the carline only is illustrated, while in the next carline to the right the edges of adjacent roof sheets are shown. The next carline towards the right has associated therewith the transverse cap 29 which is placed down over the upwardly extending stem or body portion 16 of the carline, thus straddling 50 the carline and also the upturned edges 27 of the roof sheets. The next carline to the right has its running board saddle secured in place, and as mentioned hereinbefore the rivets or the fastening means 33, normally 55 employed for securing the transverse cap to the carline, may be employed adjacent the ridge pole for also securing the running board saddle in place.

Thus it will be readily apparent that with 60 a construction as above described the assembly of the roof is not only facilitated but a rigid and durable construction is obtained. The inverted T-shaped carlines adapt themselves admirably to association 65 with the remaining elements of the frame and

have sufficient inherent rigidity to impart the necessary strength and durability thereto.

While one specific embodiment of the invention has been illustrated and described in some detail, it will be readily apparent that various changes and modifications in the specific details of construction may be resorted to without departing from the spirit and scope of this invention and to this end 75 reservation is made to make such changes as may come within the purview of the accompanying claims.

What I claim as my invention is:

1. In a flexible car roof, a skeleton frame 80 including carlines formed of T-bars, roofing sheets arranged between said carlines, transverse caps engaging the stems of said T-bars and said roofing sheets, and means for rigidly securing said caps to the stems of said T-bars at points intermediate the ridge and eaves of the car.

2. In a flexible car roof, a frame including carlines formed of inverted T-bars, roofing sheets arranged between said carlines with the edges thereof overlying the bases of said T-bars, and a transverse cap embracing and rigidly secured to the longitudinal stem of each carline at points intermediate the ridge and the eaves of the car and resiliently engaging adjacent roofing sheets.

3. In a car roof, a frame including carlines formed of inverted T-bars, roofing sheets arranged between said carlines having portions overlying the bases of said T-bars, and a transverse cap for each carline, secured to the central web thereof the said cap being provided with portions embracing said web and with additional portions spaced from said web and engaging the said portions of adjacent roofing sheets, which overlie the bases of the T-bars, the said roofing sheets having edge portions arranged between the said central web and the portions of the cap spaced therefrom and in spaced parallel relation to the same.

4. In a car roof, a frame including carlines formed of inverted T-bars, roofing sheets arranged between said carlines having offset inclined portions arranged in overlying spaced relation to the bases of the said T-bars and having upturned edge portions arranged in parallel spaced relation to the stems of the T-bars, and a transverse cap for each carline, each cap including a restricted channel portion embracing and rigidly secured to the free edge of the stem of its respective carline, an intermediate portion including sides parallel to but spaced from the stem of the carline, and outwardly turned edge portions engaging the offset inclined portions of the roofing sheet.

5. A flexible car roof including in combination carlines formed of inverted T-bars, roofing sheets arranged between said carlines,

said roofing sheets having upturned edge portions arranged in spaced relation to the stems of the said T-bars, and a transverse cap for each carline, each cap including a restricted portion embracing and rigidly secured to the free edge of the stem of its respective carline at points intermediate the ridge and the eaves of the car and an intermediate portion including sides spaced from the stem of the carline and inclosing the said upturned edge portions of the roofing sheets.

In testimony whereof I affix my signature.

EDWIN G. FRANCK.
